DESIGN FOR A SPOON OR ARTICLE OF ANALOGOUS NATURE

Application filed December 3, 1931. Serial No. 41,943. Term of patent 14 years.

To all whom it may concern:

Be it known that I, FERDINAND POPPENHÄUSER, a citizen of the United States, and a resident of Newburyport, in the county of Essex and Commonwealth of Massachusetts, have invented a new, original, and ornamental Design for a Spoon or Article of Analogous Nature, of which the following is a specification, reference being had to the accompanying drawings, forming a part thereof.

In the drawings, Figure 1 is a view of one face of a spoon showing my new design; Fig. 2 is a view showing the design in section at the line 2—2 of Fig. 1; Fig. 3 is a view similar to Fig. 2 at the line 3—3 of Fig. 1; and

Fig. 4 is a similar view to Fig. 2 at the line 4—4 of Fig. 1.

The design is delineated as embodied in the handle of a spoon but it is contemplated that the design may also be embodied in or applied to the handles of forks, knives, servers and other analogous pieces of flatware which may form part of a table service of uniform pattern.

I claim:

The ornamental design for a spoon or article of analogous nature, substantially as shown and described.

FERDINAND POPPENHÄUSER.
